AUTOMATIC SAMPLER

Russell M. Waters, Bakersfield, Calif., assignor
to Merco Nordstrom Valve Company, Pittsburgh, Pa., a corporation of Delaware

Application January 10, 1939, Serial No. 250,171

11 Claims. (Cl. 73—21)

The present invention relates to apparatus for automatically obtaining a sample from a flowing stream, and is of particular value in the transportation of crude petroleum from the wells.

It is an object of the invention to provide an automatic sampler wherein separation of constituents of the fluid to be sampled is avoided so that the removed sample is truly representative of the fluid passing through the conduit.

A further object of the invention is to provide an apparatus which will take a small sample of fluid truly representative thereof at intervals of time.

A further object is the provision of an automatic sampler in which the sample removed from the flowing stream is proportional to the quantity flowing in the conduit from which the sample is taken.

A further object is the provision of an apparatus which will automatically remove a truly representative sample from a flowing stream and wherein the quantity so removed may be adjusted or predetermined.

Still another object is the provision of an automatic sampler which is of simple construction and is easy to repair and maintain in working order.

According to the present invention I provide in a conduit carrying a moving stream of fluid, a device which is operated by the stream generally in proportion to the quantity flowing therein, and which intermittently operates a valve mechanism which is adjusted to permit escape from the conduit of a relatively small sample of the flowing fluid. Preferably, the conduit carrying the fluid to be sampled is vertical and the point of escape of the sample of fluid therefrom is substantially at the center of the flow so that the sample taken will be truly representative of the fluid in the conduit. The valve through which the sample is taken preferably is operated with a snap action, and the duration of opening may be easily adjusted so that a relatively minute sample is removed in proportion to the quantity flowing in the conduit past the valve.

The invention will be described in greater detail in connection with the accompanying drawings wherein there is disclosed a preferred modification of the invention by way of example, and in which

Figure 1 represents a vertical section taken through a conduit with the automatic sampling means shown in position.

Figure 2 is a transverse section taken on line II—II of Figure 1 showing part of the operating mechanism.

Figure 3 is a view with parts broken away taken in the direction of the arrows III of Figure 2, and

Figure 4 is an elevation of a detail.

Referring to the drawing, there is shown a

casing 1 having end flanges 2 and 3 whereby the casing may be interposed in a pipe line, and the bore 4 is adapted to form a continuation of the pipe line, the casing preferably being interposed in the pipe line in vertical position. Inside the casing 1 a shoulder 5 is provided to which a motive power unit of known construction for operating the sampler is secured. The preferred motive power unit comprises a flanged tube or working chamber 6 having a cylindrical liner 7 therein, and connected to a flanged gear case support 8 by three screws 9, the assembly being secured to the shoulder 5 by three screws 10. Radial spokes 11 integral with the tube 6 support a hub 12 in which is suitably journaled one end of the rotor shaft 13, carrying a rotor 14. The rotor 14 comprises a cup shaped shell 15 having suitable helical or inclined vanes 16 on its outer surface and is secured to shaft 13 in any suitable manner. A central deflector 17 is supported by the spokes 11 and hub 12 to relieve the fluid pressure on the rotor. The gear case support 8 comprises radial straightening vanes 18 supporting a gear case 19 thereon in which is located suitable reduction gears, and which are driven by rotor shaft 13 through a suitable coupling member 20, and a shaft 23 on the opposite side of the gear case driven by the reduction gearing carries a cam 24 of generally involute form having a high edge 25 and secured thereto by nut 26.

Below the gear case the casing 1 has a threaded bore 31 therein which receives an externally threaded hollow bearing member 32 having a flange 33 engaging the machined surface 34 of the casing. A rocker shaft 35 extends through the bore in bearing member 32 and has journals 36 and bearing 37 in the hollow bushing. A rocker arm 38 is rigidly secured to the inner end of shaft 35 to oscillate therewith, and the outer end 40 of shaft 35 is bifurcated to receive a rocker spring lever 39 which may be held in place by a cotter pin 40 passing through a transverse hole in the shaft and spring lever. The opposite end of spring lever 39 is bored to receive a bolt 41 having a transverse pivot pin 42 therein which rests against the upper surface of spring lever 39. An L-shaped abutment 43 is secured to the casing by screws or other suitable means, and the upper end of a spring 44 on bolt 41 engages the abutment 43. The lower end of spring 44 engages a washer 45 on bolt 41 which is held in position thereon by lock nuts 46. A cover 47 encloses the rocker shaft spring assembly and is held in fluid tight relation by bolts 48, a suitable gasket 49 being interposed to prevent leakage. It will be apparent that spring 44 biases shaft 35 clockwise as viewed in Figure 3, and thus holds the upper end of arm 38 against cam 24.

Rocker arm 38 carries a trigger mechanism comprising a bifurcated trigger piece 51 which

receives the lower end of the rocker arm 38 within the bifurcation and is secured thereto by a pivot pin 52 passing through the trigger piece and rocker arm which is retained against removal by a cotter pin 53. A shouldered pin 54 is riveted through the bifurcated end of the trigger piece and a trigger spring 56 has one end secured to said pin and the other end passes through a hole 58 in the rocker arm 38, and thus biases the trigger piece counterclockwise, as viewed in Figure 1. The end 59 of the trigger piece has a valve engaging shoulder 61 and a release portion 62 for a purpose presently to be described.

The casing has a threaded hole 63 which receives the reduced threaded portion of a sampling tube 64 and a gasket 66 engaged by a shoulder 67 formed by an enlarged portion of the tube prevents leakage between the sampling tube and casing. The bore 68 in the sampling tube tapers to an orifice 69 at the inner end thereof and the exterior of the tube is tapered at 71 to form a nozzle. The orifice 69 of the sampling tube preferably is located at the center of the passage 4 so that a sample removed therefrom will be truly representative of the material passing through the casing. Diametrically opposite the sampler tube 64 the casing is bored and threaded at 73 to receive a hollow threaded bushing 75 held in position by a jamb nut 76. The bushing 75 may be adjusted axially and leakage around the threaded bushing 75 is prevented by an annular plastic packing 77 located in an annular recess 78 which is compressed therein by a suitable packing screw 79 passing through a radial threaded bore 81 communicating with the packing chamber 78. The bushing 75 has a bore 82 adapted to receive a piston 83 carrying a valve seat insert 84 at its inner end adapted to engage the nozzle 71 of the sampler tube 64 and close the orifice 69 therein. The piston 83 is relieved at 86 to provide an equalizing chamber communicating by radial bores 87 with the interior of the casing, and bores 88 connect the bore 82 behind the piston 83 with the interior of the casing 1. The valve piston has an extension 89 with a flange 91 thereon received in the bore 81 which serves as one abutment for a spring 92, the other end of spring 92 abutting an adjustment screw 94 threaded into the outer end of bore 82. Screw 94 has a kerf therein whereby it may be turned with a screw driver. Centering projections 96 and 97 are provided to maintain the spring in proper alignment. The outer end of bore 81 is closed by a threaded pipe plug 98.

The valve piston 83 has a shoulder 99 adapted to be engaged by the valve engaging shoulder 61 of the trigger piece, whereby the valve is moved away from the sampler tube, and the inner end of bushing 75 is tapered as indicated at 101 to provide a release cam which co-operates with the release portion 62 of the trigger member to limit the opening of the valve. The sampling tube 64 has a reduced portion 103 at its outer end forming a shoulder 104, and a receiving member 105 has a bore 106 which receives the reduced portion 103 and is counterbored at 107 to provide a sealing shoulder 108, a gasket being interposed between the shoulders 104 and 108. The end of bore 68 is threaded and receives the threaded end of the cap screw 110 extending through the receiving member, whereby the receiving member is held in position on the sampler tube. The receiving member is hollowed out at 111 and a cross bore 112 in the sampler tube end provides communication with passage 75

111 which extends through the cap 113. A sample receiving jar 114 may be secured in any suitable manner to the cap 113, as shown, the jar being secured by a bail 115.

5 To prevent development of too high a pressure in the sample receiving jar 114, a safety valve 117 is provided comprising a threaded bushing 118 received in a threaded bore 119. The bushing terminates in an enlarged internally threaded 10 cylindrical portion 121 which receives an inverted cup shaped member 122 having a release valve 123 therein. Release orifices 125 are provided communicating with the interior of cap 122.

15 The release valve 123 comprises a piston providing a valve surface which co-operates with the seat 126 in the bushing 118, and a spring 127 in the cup 122 abuts against the valve to hold it against the seat. The seating pressure of spring 126 may be adjusted by threading the cup 122 into or out of the cylindrical member 121.

20 The operation of the apparatus now will be described. The casing 1 is installed on a pipe line so that the flow therethrough is vertically upward, and the fluid passing through the straightening vanes 18 enters the working chamber and causes the rotor 14 to rotate in known manner.

25 The rotary motion of rotor 14 and shaft 13 is transmitted through the reduction gearing in gear case 19 and causes rotation of the involute cam 24 on the driven shaft 23. Assuming the cam to be in position with the high edge 25 of the cam in contact with the rocker arm 38, the trigger mechanism 51 will be in the position shown in Figure 1 with the valve engaging shoulder 30 61 against the shoulder 99 on the valve. Upon further rotation of the cam 24 by the rotor 14 the rocker arm 38 will reach the radial portion of the cam and will be released suddenly, thus allowing the rocker spring 44 to rotate rocker 40 arm 38 clockwise as viewed in Figure 1 and move the valve seat 84 away from the sampler tube orifice 69, and as this movement is continued the released portion 62 of the trigger engages the tapered release cam 101, thus releasing the shoulders 61 and 99, whereupon spring 92 returns the valve to close the orifice 69.

45 During the interval that the orifice 69 is open, the pressure of the fluid in the casing 1 forces a small quantity of the flowing liquid through the orifice 69 and bore 68 which passes through the cross bore 112 from the sampler tube into the sampler passage 111 and into the receiving jar 114. In the meantime the cam 24 continues to revolve and slowly moves the upper end of rocker arm 38 to the left to cause the arm to rotate counterclockwise about the rocker shaft 35 and the trigger mechanism is gradually brought to the right until the valve engaging shoulder 61 again engages the shoulder 99 of the valve piston. By this time the upper 50 end of rocker arm 38 is at the high point of cam 24 and upon further rotation of cam 24 the operation previously described for opening the valve is repeated. It will be observed that the orifice 69 of the sampler tube is substantially at the center of the casing 1. This location has the advantage that a more truly representative sample of the fluid is obtained and separation of the constituents of the fluid by change in direction of flow is reduced to a minimum. The degree of 55 opening of valve member 84 may be adjusted by the threaded bushing 75. Turning the bushing inwardly provides a smaller duration of opening for the valve than when the bushing is adjusted outwardly. The plastic packing around the threads of the bushing provides an adequate

seal which enables this adjustment to be made. The speed with which the valve member 84 is moved also may be determined by adjustment of the pressure on spring 92. Safety valve 117 preferably is set to maintain closed against the pressure in the casing 1. However, crude petroleum contains dissolved gases and when the sample in the jar 114 is subjected to changes in atmospheric temperature such as are normally encountered in the oil fields, the pressure in the jar may become too high. Under such conditions the safety valve 123 opens to permit the escape of excess pressure.

Having described my invention, what I desire to claim and secure by Letters Patent is:

1. An automatic sampler comprising a conduit carrying a moving stream of fluid, means in said conduit operated by the flow of fluid therethrough, a tube extending into the flowing stream in said conduit, said tube having a passageway therethrough terminating in an orifice, a valve in said conduit for normally closing said orifice, and snap action means operated by said first mentioned means for operating said valve member with a snap action.

2. A sampler mechanism comprising a conduit for carrying a stream of fluid, means in said conduit operated by the flow of fluid therethrough, means projecting through said fluid substantially to the center of the flowing stream, said latter means having an orifice therein whereby a sample may be removed, and a valve in said conduit operated by said first mentioned means for opening and closing said orifice.

3. A sampler mechanism comprising a conduit for carrying a stream of fluid, means in said conduit operated by the flow of fluid therethrough, means projecting through said fluid substantially to the center of the flowing stream, said means having an orifice therein whereby a sample may be removed, a valve for normally closing said orifice, snap action means operated by said first mentioned means for operating said valve, and means for adjusting duration of the open position of said valve.

4. An automatic sampler comprising a conduit, means operated generally in proportion to the flow of fluid through a conduit, said conduit having a passageway therethrough terminating in an orifice, a valve member adapted to close said orifice and having a shoulder thereon, a rocker arm, a trigger member carried by said rocker arm and having a portion adapted to engage said shoulder, a release cam positioned in the path of said trigger, and means operated by said first mentioned means for oscillating said rocker arm.

5. An automatic sampler comprising a conduit, means operated generally in proportion to the flow of fluid through a conduit, said conduit having a passageway therethrough terminating in an orifice, a valve member adapted to close said orifice and having a shoulder thereon, a rocker arm, a trigger member carried by said arm and having a portion adapted to engage said shoulder, a release cam positioned in the path of said trigger, means operated by said first mentioned means for oscillating said rocker arm, and means for adjusting the position of the release cam.

6. An automatic sampler comprising a conduit,

a bushing adjustably threaded into said conduit, means for locking said bushing in position, a bore in said bushing, a valve member including a stem operating in said bore, adjustable spring 5 means urging said valve in one direction, means having an orifice therein co-operating with said valve for removing a sample of fluid from the conduit, means adapted to be operated generally in proportion to the flow of fluid through said conduit, trigger means operated by said last named means to open said valve, and means on said trigger means adapted to engage said bushing for releasing said valve.

7. An automatic sampler comprising a conduit, means operated generally in proportion to the flow of fluid through said conduit, a rocker arm shaft extending into said conduit, a rocker arm secured thereto, spring means biasing said rocker arm and shaft in one direction, said 15 first mentioned means moving said rocker arm against the bias of said spring means, a sampler valve opened upon movement of said rocker arm in one direction, means for releasing said sampler valve from the rocker arm, and means independent of the rocker arm for closing said valve.

8. An automatic sampler comprising a conduit adapted to carry a moving stream of fluid, rotary means in said conduit operated by the flow of fluid therethrough, a valve orifice provided in 20 said conduit removed from the area of turbulence caused by said rotary means whereby a sample of fluid may be removed from said conduit, a valve in said conduit for normally closing said orifice, and snap action means operated by said 25 rotary means for operating said valve member with a snap action.

9. An automatic sampler comprising a conduit for the flow of fluid, a receiver, an orifice provided for the escape of a sample quantity of fluid from the conduit to said receiver, a valve member for closing said orifice, snap action means for operating said valve, means adapted to be operated by the flow of fluid in said conduit to operate said snap action means, and means for adjusting the opening period of the valve member 40 to determine the quantity of sample removed to the receiver.

10. In an automatic sampler, a conduit, a guide bushing in said conduit having a bore 45 therein closed at its outer end, a valve member having a piston operating in said bore, means substantially balancing fluid pressure on opposite sides of said piston, spring means urging said valve in one direction, means having an orifice therein co-operating with said valve for removing a sample of fluid from said conduit, and means for periodically operating said valve with a snap action.

11. An automatic sampler comprising a conduit, a guide bushing in said conduit having a bore therein closed at its outer end, a valve member having a piston operating in said bore, spring means urging said valve in one direction, means having an orifice therein co-operating with said valve for removing a sample of fluid from said conduit, means for periodically opening said valve, release means on said bushing to release said opening means to allow snap closing of the valve, and means to adjust said release means to determine the quantity of sample removed.

RUSSELL M. WATERS.
